HEEL BREASTING MACHINE

Howard B. Munson, Chicago, Ill., assignor to
Wilder & Company, Chicago, Ill., a corporation
of Illinois

Application April 7, 1939, Serial No. 266,530

11 Claims. (Cl. 12—47.1)

The invention relates to improvements in heel
breasting machines and has for its primary ob-
ject the provision of an improved machine of
the character indicated which is capable of
5 quickly, accurately, uniformly and artistically
shaping and dressing the breasts of heel blanks
for use in the making of shoes.

Another object of the invention is the provi-
sion of a machine of the character indicated so
10 constructed and arranged that the form and
shape of the heel breast formed may be varied
as desired and more particularly may be cut or
dressed with straight edges.

Other objects will appear hereinafter.

15 The invention consists of the combinations and
arrangements of parts hereinafter described and
claimed.

The invention will be best understood by ref-
erence to the accompanying drawings forming
20 a part of this specification and in which

Fig. 1 is a front view of a portion of a machine
embodying the invention;

Fig. 2 a side view thereof;

Fig. 3 a top plan view of the machine;

25 Fig. 4 is an enlarged partial horizontal section
taken substantially on line 4—4 of Fig. 2;

Fig. 5 an enlarged vertical section taken sub-
stantially on line 5—5 of Fig. 1;

30 Fig. 6 an enlarged detail view of the machine
taken on line 6—6 of Fig. 4;

Fig. 7 a side view of a heel blank before cut-
ting or dressing;

Fig. 8 a top plan view of said heel blank;

35 Fig. 9 a vertical section of a heel blank after
the breast thereof has been cut and dressed in
the machine; and

Fig. 10 a top plan view of said cut heel blank.

The embodiment of the invention illustrated
in the drawings is in the form of attachments or
40 additions added to an ordinary well known hand
milling machine. Briefly and generally this mill-
ing machine comprises a suitable support or
standard having a laterally extending supporting
bracket 11 vertically and laterally adjustable
45 thereon. A work table 12 is mounted as shown
on the supporting bracket 11 to slide horizontally
on a guide 13 and carries a depending rack bar
14 meshing with a pinion 15 on an operating
shaft 16 carrying an operating handle 17 so con-
50 structed and arranged that the work table 12
may be slidably and manually adjusted hori-
zontally on the guide 13 by manipulations of the
handle 17 in the usual way.

The frame of the machine is also provided
55 with an upstanding supporting standard 18 hav-

ing a vertical guide 19 thereon and a cutter head
20 is mounted in the usual way to slide vertically
in the guide 19. The vertical reciprocations of
the cutter head 20 are controlled by a handle
lever 21 carrying a segmental gear 22 meshing
5 with the usual rack bar 23 in the guide 19. The
cutter head 20 also carries the usual cutter shaft
24 projecting laterally therefrom in cooperative
relationship with the work table 12. Shaft 24
also carries the usual driving pulley 25 connected
10 by belt 26 with pulley 27 on the driven shaft
28 of the machine. The outer or free end of the
shaft 24 is further supported by a conical bearing
29 in a bracket 29 adjustably clamped as in-
dicating on the usual supporting rod 30. 15

So much of the machine as has already been
described constitutes the main working parts of
an ordinary well known hand milling machine
and constitutes no part of my present invention
except in so far as the same cooperates with the
20 attachments thereto to be presently described.

A clamping member having a base 31 is ad-
justably mounted and secured on the work table
12 by means of clamping bolts 32 and is pro-
vided with an upstanding support or standard 25
33 as best shown in Figs. 2 and 1. A heel clamp
rest 34 is adjustably arranged as shown at the
top of the standard 33 and is provided with two
positioning pins 35 adapted to enter correspond-
ing openings in the bottom of a heel blank 30
thus accurately position the same on said rest.
A clamping head 36 is arranged as shown to co-
operate with the rest 34 to clamp a heel blank
thereon, said head being adjustably mounted as
shown upon a yoke 37 carried by the upper ends 35
of vertically reciprocating rack bars 38 project-
ing upwardly from the standard 33. The rack
bars 38 mesh with operating pinions 39 on an
operating shaft 40 which is operated by a handle
lever 41. Handle lever 41 carries a spring held
pawl 42, best shown in Fig. 4, said pawl cooper-
ating with a segmental ratchet wheel 43 on the
standard 33 to lock said handle lever 41 in vari-
ous positions of adjustment. The operation of
the pawl 42 is controlled by a cam lever 44 op-
erating to release the lever 41 when the same
is grasped in the hand as will be readily under-
stood. By this arrangement, the clamping head
36 may be readily adjusted to clamp a heel blank
on the heel rest 34, as will be readily understood. 50

The standard 33 also carries a cam plate 45
provided on its rear face with a cam surface 46,
said cam plate 45 being pivoted at 47 on said
standard and rendered angularly adjustable
thereon by means of a slot and bolt connection 55

48, as best shown in Fig. 6, and whereby said cam plate 45 may be angularly adjusted on said standard, as will be readily understood.

As best shown in Figs. 1 and 5, a revolving cutter 49 is mounted upon the cutter shaft 24 so as to move vertically across the breast of a heel blank clamped on the heel rest 34 as indicated by the dotted lines in Fig. 5. A guard 50 for the cutter 49 is adjustably mounted on the supporting rod 30, as indicated. A supporting bracket 51 is also adjustably clamped as indicated on the supporting rod 30 and carries a cam contact member 52 projecting as shown in cooperative relationship with the cam surface 46 on the cam plate 45 so as to be brought in cooperative contact therewith when the cutter 49 is in operation, as will be readily understood.

In operation, a heel blank 53, such as is illustrated in Figs. 7 and 8, first properly positioned 20 on the heel rest 34 is securely clamped thereon by means of the clamping head 36. Then, by manipulating the handles 41 and 21, the operator passes the cutter 49 vertically along the breast of the heel blank while holding the contact member 50 in cooperative sliding relationship with the cam surface 46 on the cam plate 45. As will be noted, the sides of the heel blank 53 are curved and dressed in the usual way and the cutter 49 is also shaped to cut the breast of the 30 heel on a curve, as best indicated in Fig. 10. Obviously the intersection between the curve which would be cut by the cutter 49 applied to a stationary heel blank, would be some kind of a curve which is undesirable at the front edges of the 35 heel blank. The cam surface 46 is therefore so shaped with relation to the curvature of the cutter 49 as to cause corresponding approach and recession of the heel blank during the cutting operation as to cause the edges 55 to be 40 formed on straight lines as indicated in Figs. 9 and 10. A very desirable result in the artistic appearance of the edges of the heels may thus be readily obtained. By adjusting the angularity of the cam plate 45, the edges 55 of the heel blank 45 may be cut straight but on slanting lines as and when desired. In this way, heel blanks may be accurately, uniformly and quickly cut or dressed so as to require a minimum of scouring or polishing before incorporated in the shoe. The specific form and arrangement of parts disclosed is 50 a simple and effective one for the purpose.

While I have illustrated and described the preferred form of construction for carrying the invention into effect, this is capable of variation 55 and modification without departing from the spirit of the invention. I therefore do not wish to be limited to the precise details disclosed, but desire to avail myself of such variations and modifications as fall within the scope of the appended claims.

I claim:

1. A machine of the class described comprising a heel blank clamping member; a cutter member adapted to shape the breast of a blank in 65 said clamp; means for causing relative move-

ment between said members in the direction of the height of the heel blank to effect such shaping; and means for causing said members to slidably approach and recede transversely of the said direction of movement and during and 5 simultaneously with said shaping movement.

2. The machine specified in claim 1 in which a revolving cutter member is employed.

3. The machine specified in claim 1 in which the means for causing the approach and recession of said members consists of a cam on one of them and a coacting contact on the other.

4. The machine specified in claim 1 in which a revolving cutter member is employed and the means for causing said members to approach and 15 recede consists of a cam on one of them and a coacting contact on the other.

5. The machine specified in claim 1 in which a revolving cutter member is employed and the means for causing said members to approach and 20 recede from each other consists of a replaceable and angularly adjustable cam on one of said members and a coacting contact on the other.

6. A machine of the class described comprising a heel blank clamp; a cutter mounted to move along the height of the breast of a heel blank in said clamp and shape the same; and means for causing said clamp to slidably approach and recede transversely of the path of 25 said cutter during and simultaneously with said 30 shaping movement.

7. The machine specified in claim 6 in which a revolving cutter is employed.

8. The machine specified in claim 6 in which the means for causing the clamp to approach 35 and recede consists of a cam on said clamp and a coacting contact on the cutter.

9. The machine specified in claim 6 in which a revolving cutter is employed and the means for causing said clamp to approach and recede consists of a replaceable and angularly adjustable 40 cam on said clamp and a coacting contact on the cutter.

10. A machine of the class described comprising a suitable supporting frame; a heel blank 45 clamping member mounted to reciprocate on said frame; a handle lever operatively connected with said clamping member to effect reciprocations thereof; a revolving cutter mounted to reciprocate on said supporting frame in cooperative relationship with and substantially perpendicular to the path of said clamping member and shaped to cut the breast of a heel on a suitable curve; a handle lever operatively connected with said cutter to cause its reciprocations; and a 55 cam on said clamping member, cooperating with a contact on said cutter and so constructed and arranged as to cause approach and recession of said clamping member during reciprocation of said cutter to cut the edges of the breast of the 60 heel on substantially straight lines.

11. The machine specified in claim 10 in which the cam is replaceable and angularly adjustable.
